UNITED STATES PATENT OFFICE.

WILLIAM H. KREMER, OF CANTON, ILLINOIS.

DESIGN FOR A BUTTER-JAR.

SPECIFICATION forming part of Design No. 30,087, dated January 31, 1899.

Application filed January 3, 1899. Serial No. 701,048. Term of patent 7 years.

To all whom it may concern:

Be it known that I, WILLIAM H. KREMER, of Canton, in the county of Fulton and State of Illinois, have invented a certain new Design 5 for Butter-Jars, of which the following is a specification.

In the drawings forming part of this specification, Figure 1 is a perspective representation of a jar made in accordance with my design. Fig. 2 is a central vertical section through the jar, and Fig. 3 is a plan thereof.

The material features of the design reside in the configuration of the jar, together with the annular rib encircling the jar, near the 15 upper end thereof.

The jar 1 is circular in cross-section, and it flares slightly and uniformly from its bottom to its top. The bottom 3 of the jar joins to the side in curved lines, giving the outer 20 edge of the bottom a rounded-off appear-

ance, and the central part of the bottom is bulged up slightly to form a concavo-convex surface. Near the upper end of the jar, on the outer side thereof, is extended an annular rib 2. The interior of the jar is smooth, 25 with the diameter thereof increasing gradually from bottom to top, and the outer surface is provided with the annular rib or band near its upper end.

What I claim is—

The design for a butter-jar herein shown and described.

In testimony whereof I sign my name in the presence of the subscribing witnesses.

W. H. KREMER.
